J. E. DAVIS

SOUND AMPLIFYING MEANS

Filed Jan. 26, 1924

Fig. 2.

Inventor
John E. Davis
By his Attorney *John B. Seifert*

UNITED STATES PATENT OFFICE.

JOHN E. DAVIS, OF BROOKLYN, NEW YORK.

SOUND-AMPLIFYING MEANS.

Application filed January 26, 1924. Serial No. 688,714.

To all whom it may concern:

Be it known that I, JOHN E. DAVIS, a citizen of the United States, and a resident of the borough of Brooklyn, in the county of 5 Kings, city and State of New York, have invented certain new and useful Improvements in Sound-Amplifying Means, of which the following is a specification.

This invention relates to means to amplify 10 sound waves caused by the human voice or by the vibratory diaphragm of a sound reproducing device, telephone, radio receiving apparatus and other acoustic devices, and it is the object of the invention to provide a 15 sound amplifier of this character which is novel, compact and cheap in structure, and highly efficient in the enhancing and propagating of sound waves, and which is capable of absorbing distorted sound waves of overtones and magnifying the sound waves of 20 dominant and undertones.

In carrying out the invention I provide a tubular receiver for the sound waves which are to be augmented and magnified and arrange 25 a vibratory wall in spaced relation around said receiver. This wall is preferably of truncated cone shape and rectangular shape in cross section with the small end closed and supported practically without 30 stress or strain. This wall is in the nature of a sounding board for which purpose it is preferably made of relatively thin wood having alternate relatively hard and soft or spongy growth rings quarter sawed across 35 the natural growth rings whereby said growth rings or grain will extend longitudinally and in the structure of the amplifier extend in parallelism and longitudinally of the axis of the conical member. The sound 40 receiver is connected to and supported from the conical member intermediate its ends and sides and through which means the sound waves entering the receiver are transmitted to the sounding board to vibrate the latter in consonance therewith the dominant 45 tones of such sound vibrations being magnified by the hard layers of the growth rings of the wood and the overtones being absorbed in the soft spongy layers alternating 50 with said hard layers. The receiving end of the receiver is preferably arranged at the open end of the conical member and extends axially of and to adjacent the closed end of 55 said conical member, the sound waves emerging from the outlet end of the receiver being impinged against the closed end of the

conical member and thereby reflexed outward and act to exert a directive force outward from the conical member and of the waves set up by the vibration thereof and 60 transmitted thereto from the receiver.

In the drawing accompanying and forming a part of this specification, I have shown an embodiment of the invention in which Figure 1 is a longitudinal sectional view 65 and showing the manner of mounting the same, and

Figure 2 is a perspective view with a part of the mounting and enclosing casing removed and a part thereof shown in section. 70

The embodiment of the invention illustrated in the drawing comprises a truncated cone shaped member 3, preferably of rectangular shape in cross section, which member is constructed of wood having alternating 75 relative hard and soft spongy growth rings, spruce being preferred and having been found to function efficiently for the purpose, although it is to be understood that other wood having the same growth characteristics may be utilized, said wood being quarter sawed or sawed across the natural growth rings whereby the grain of the wood or board will extend in parallel relation longitudinally of the board, and in the structure of the conical member said grain will extend longitudinally of the axis thereof. The smaller end of said member 3 has a closure 4 of wood attached thereto which may also be of the same material as the side 80 walls.

A tubular receiver 5, which is also preferably of conical form, the wall diverging from the receiving end 6 to the opposite end 7, and of rectangular shape in cross section, 85 is mounted in the truncated cone sounding board 3 to extend thereinto from the enlarged end to adjacent but in spaced relation to the closed end 4, the receiving end being at the larger open end of the conical member with the latter extending around and in spaced relation to the receiver as clearly shown in the drawing. The receiver is also made of wood having a grain consisting of alternating hard and soft or spongy layers 100 extending longitudinally thereof.

To transmit the vibrations set up in the receiver by the transmission of sound waves therethrough the receiver is connected to and supported from the conical sounding 110 board 3 by bridge pieces 8 engaging edge-wise between the receiver and conical mem-

ber intermediate the ends and substantially midway between the sides thereof, said bridge pieces having been found to function efficiently by having the same engage for the full length thereof with the receiver and secured thereto, as by gluing, and having a portion cut from the opposite longitudinal edge intermediate its ends, as at 9, whereby only a relatively small part of said edge of 10 the bridge pieces and at opposite ends will engage with the wall of the sounding board. The receiver and bridge pieces are held in position relative to the sounding board substantially without stress or strain, screws 10 being shown for this purpose passing 15 through the sounding board and engaging in the bridge pieces.

In order that the amplifier will function properly the amplifying unit, comprising 20 the conical sounding board with the sound wave receiver, is mounted in a support without stress or strain upon the vibratory actions of the sounding board for which purpose it is mounted at the outer or enlarged 25 end of the conical member. In the present instance it is mounted in a carrying casing 11 extending around in spaced relation and closing the sides and closed end of the conical member and having an open end at the 30 enlarged open end of the conical member the latter being secured in said casing by screws 12 passing through the edge portion of the conical member substantially midway between the sides and engaging in the casing 35 with a cushioning member 13 interposed between the conical member and casing, as clearly shown in the drawing. A grille 14 may be attached to the open end of the casing and amplifier.

40 The amplifier may be used as a megaphone for augmenting and magnifying the sound of the human voice directly in which case the user talks directly into the receiving end 6 of the receiver 5. To use the device for amplifying reproduced sounds, as 45 by a vibratory diaphragm either mechanically or electrically operated, a diaphragm carrier or microphonic unit, designated in a general way at 15, is mounted directly in a 50 the receiving end of the receiver, for which purpose a reinforcement, as shown at 14', is arranged at the receiving end of the receiver, this reinforcement means consisting of a layer of wood similar to the material 55 of which the receiver is made with the grain extending longitudinally of the receiver.

While I have illustrated and described one manner of construction and arrange-

ment of my improved sound amplifier it will be obvious that the invention is not to be limited to such construction and arrangement and that variations and modifications may be made in structure and form and that portions of the invention may be used without others and come within the scope of the invention.

Having thus described my invention I claim:

1. In a sound amplifier, a sounding board of truncated cone shape closed at the smaller 70 end, a sound receiver axially of the sounding board with the sound receiving end at the open end thereof, and a bridge connection between the sounding board and the receiver through which the vibrations of the 75 sound waves are transmitted from the receiver to the board, said sounding board being supported at the open end only.

2. In a sound amplifier, a sounding board of truncated cone shape having a closure at 80 one end, a tubular sound receiver extending into the sounding board axially thereof to adjacent the closed end and having the receiving end at the open end of the sounding board, means to connect the receiver to and support the same from the sounding board intermediate the ends to transmit the sound vibrations therethrough from the receiver to the sounding board and reflex said sound waves outwardly, and means to support the 85 sounding board at the open end substantially without stress or strain.

3. In a sound amplifier, a member of rectangular shape in cross section having one end closed, said member being constructed 90 of quarter sawed wood with the grain extending in parallel relation and longitudinally of the axis thereof, a tubular sound wave receiver to extend axially into said member to adjacent the closed end and with the receiving end at the open end of said member, bridge pieces to connect and support the receiver from said member between the ends thereof constructed and arranged to transmit the vibrations of the 100 sound waves from the receiver to the wall of said member, an open end casing in which the rectangular member is supported substantially without stress or strain at the open end with said end at the open end of 105 the casing, and an open grille closure for the open end of the casing.

Signed at New York city, in the county of New York and State of New York this 23rd day of January, 1924.

JOHN E. DAVIS.
